LOOM SHUTTLE BOX

Carl D. Brown, Hopedale, Mass., assignor to
Draper Corporation, Hopedale, Mass., a corpora-
tion of Maine

Application February 19, 1934, Serial No. 711,830

6 Claims. (Cl. 139—185)

The present invention pertains to loom shuttle boxes and has more particular reference to the construction of the back box plate thereof.

The conventional shuttle loom includes a reciprocating lay which carries a shuttle box at each end thereof, and a reed extending between the shuttle boxes. The back wall or box plate of each shuttle box is pivoted or otherwise secured at its outer end to the lay, and is provided with a shuttle guiding surface adapted to be aligned with the reed. It has been proposed to provide for adjustment of the shuttle guiding surface by making the back box plate in two separate pieces pivotally connected together as by means of a universal joint. Such prior construction is highly efficient in providing for the initial alignment of new box plates with a given reed but does not provide for ready re-alignment with a different reed after the box plate is once installed.

It frequently happens that in changing the character of cloth woven on a particular loom a different reed will be required. At other times, when the reed becomes worn it will be reversed to present a new wearing surface to the shuttle. Lack of uniformity in reed construction usually necessitates a re-alignment of the back box plate each time the reed is so reversed or changed. The present invention accordingly contemplates the provision of a back box plate which is constructed to facilitate its alignment or re-alignment with the reed.

In accomplishment of the result mentioned, I have provided for adjustment of the inner end of the box plate by adjusting means which include a resilient pad between the box plate and the lay sword, and adjusting elements such as screws carried by the sword. Preferably, the box plate is comprised of outer and inner members which are pivotally connected together, as by means of a universal joint, the shuttle guiding surface being provided on the inner member. An adjustable pivot may be provided at the outer end of the shuttle guiding surface to facilitate alignment of the shuttle guiding surface in a manner hereinafter explained in detail.

For detailed disclosure of the preferred embodiment of my invention reference may be had to the accompanying drawing, of which:

Fig. 1 is a plan view of the right hand end of the lay and the right hand shuttle box;

Fig. 2 is a horizontal sectional view showing the back box plate and lay sword; and

Fig. 3 is an elevation showing the shuttle box as viewed from the back of the lay.

The lay 1 is but fragmentarily illustrated, only the right hand end thereof being shown. The lay is slotted at 2 for the reception of a picker stick 3 which carries a picker 4 for picking the shuttle 5. The lay is carried upon lay swords of which only the right hand sword 6 is shown. The elements thus far mentioned are old in the art and may be of any suitable usual construction.

The shuttle box is comprised of a front box plate 7, of usual construction, and the back box plate of the present invention. The back box plate is preferably comprised of an outer member 8 and an inner member 9, the right hand end of the right hand shuttle box being considered the "outer" end thereof and the end opening toward the center of the lay being the "inner" end. The outer member 8 is attached at its outer end to the lay, as by being pivoted upon a bolt 10 which passes down through a metal flange 11 on the lay. A binder 12 of conventional design is pivoted upon bolt 10 and actuated by a binder spring 13.

The inner member 9 is provided with a shuttle guiding surface 14 which is adapted to be aligned with the reed (not shown). The inner member is also preferably provided with an overhanging ledge 15, of conventional design, for limiting vertical movement of the shuttle. In order to provide for relative adjustment between the members 8 and 9 they are pivotally connected together by suitable means such as a universal joint 16. The universal joint shown is not, per se, of the present invention, it being disclosed and claimed in Patent No. 1,848,674, granted March 8, 1932, to W. I. Simpson. Other pivotal connections may be employed if so desired.

The outer end of the inner member 8 is provided with a rearwardly extending flange 17 the end of which is turned downwardly and threaded to receive a lay-engaging screw 18. The point of the screw 18 is positioned at about the outer end of the shuttle guiding surface 14 and provides a pivot point about which the said surface may be swung. Since the screw 18 is adjustable it may be utilized to vary the position of the pivot point relative to the shuttle guiding surface.

The inner end of the member 9 is secured to the lay sword 6 through the medium of vertically spaced screws 19 which pass loosely through the sword and are threaded into said member. A resilient pad 20, preferably of rubber, is positioned between the inner member and the lay sword. It will be noted that the member

9 is slightly thicker at 21 outwardly of screws 19 than at 22 inwardly of said screws. The pad 20 will accordingly be compressed more where it contacts the thickened portion 21, which 5 serves to hold the pivot screw 18 against the lay. The screws 19 may be tightened or loosened substantially simultaneously, in which event the shuttle guiding surface will be pivoted about a vertical axis passing through the point of pivot 10 screw 18. On the other hand, the holes 23 in the lay sword for the screws 19 are sufficiently large to permit either one of these screws to be tightened or loosened independently of the other, thus pivoting the shuttle guiding surface 15 about a horizontal axis passing through the point of the pivot screw 18.

The preferred method of adjusting the box plate is as follows:

First, the universal joint 16 is loosened slightly. 20 Then the pivot screw 18 is adjusted to align the outer end of the shuttle guiding surface with the reed. Then the screws 19 are adjusted to vertically and horizontally align the inner end of the shuttle guiding surface with the reed and, 25 finally, the universal joint is tightened thereby firmly securing the parts in adjusted position.

It will be apparent that I have provided means for rapidly and accurately aligning or re-aligning the shuttle guiding surface of the back box 30 plate with the reed, the desirability of such a construction having been previously explained.

Having fully disclosed the preferred embodiment of my invention, I claim:

1. A back box plate for looms, said box plate 35 being comprised of an outer member adapted to be attached to a loom lay, an inner member provided with a shuttle guiding surface, an adjustable pivot at the outer end of said shuttle guiding surface, adjusting means for adjusting said inner member about said pivot, and means 40 pivotally securing said inner member to the inner end of said outer member at a point intermediate said adjustable pivot and said adjusting means.

2. A back box plate for looms, said box plate 45 being comprised of an outer member adapted to be pivotally attached at its outer end to a loom lay, an inner member provided with a shuttle guiding surface, an adjustable lay-engaging 50 element at the outer end of said shuttle guiding surface which element provides a pivot point about which said inner member may pivot, adjusting means for adjusting said inner member about said pivot point, and means pivotally securing said members together at a point intermediate the ends of said inner member.

3. A back box plate for looms, said box plate being comprised of an outer member adapted to be pivotally attached at its outer end to a loom lay, an inner member provided with a shuttle guiding surface, an adjustable lay-engaging screw at the outer end of said shuttle guiding surface which screw provides a pivot point about which said inner member may pivot, and adjusting means for universally adjusting said inner member about said pivot point, said members being connected by a universal joint. 85

4. In a loom, the combination of a lay adapted to carry a reed, a lay sword, and a shuttle box carried on said lay; said shuttle box including a back box plate comprised of an outer member pivotally secured at its outer end to the lay and an inner member provided with a shuttle guiding surface, said members being connected by a universal joint, and means for adjustably securing the inner end of said inner member to the lay sword, said means including a resilient pad between said inner member and said lay sword. 90

5. In a loom, the combination of a lay adapted to carry a reed, a lay sword, and a shuttle box carried on said lay; said shuttle box including a back box plate comprised of an outer member pivotally secured at its outer end to the lay and an inner member provided with a shuttle guiding surface, said members being pivotally connected by a universal joint, an adjustable screw at the outer end of said shuttle guiding surface the point of which screw provides a pivot point for said inner member, and means carried by the lay sword for adjusting said inner member about both a vertical and a horizontal axis passing through said pivot point. 100

6. In a loom, the combination of a lay adapted to carry a reed, a lay sword, and a shuttle box carried on said lay; said shuttle box including a back box plate comprised of an outer member pivotally secured at its outer end to the lay and an inner member provided with a shuttle guiding surface, said members being pivotally connected by a universal joint, an adjustable screw carried by said inner member at the outer end of said shuttle guiding surface the point of which screw engages the lay to provide a pivot point for said inner member, and means including spaced screws carried by the lay sword and a resilient pad between said inner member and said lay sword for adjusting said inner member about both a vertical and a horizontal axis passing through said pivot point. 115
